[57] CLAIM

The ornamental design for a segmented turtle-shaped pendant or similar article, substantially as shown and described.

DESCRIPTION

FIG. 1 is a perspective view of a segmented turtle-shaped pendant or similar article showing my new design;

FIG. 2 is a top plan view thereof;

FIG. 3 is a bottom plan view thereof;

FIG. 4 is a side elevational view thereof, as viewed from the right of FIG. 2;

FIG. 5 is a side elevational view thereof, as viewed from the left of FIG. 2;

FIG. 6 is a rear elevational view thereof;

FIG. 7 is a front elevational view thereof; and

FIG. 8 is a top plan view of the pendant which shows the segments separated relative to each other.

For convenience of illustration, portions of the chain are omitted in various figures of the drawing.
